UNITED STATES PATENT OFFICE.

CLAUDE HURN, OF CENTRALIA, WASHINGTON.

MUSIC-LEAF TURNER.

1,288,899.

Specification of Letters Patent. Patented Dec. 24, 1918.

Application filed August 13, 1917. Serial No. 186,002.

To all whom it may concern:

Be it known that I, CLAUDE HURN, a citizen of the United States, residing at Centralia, in the county of Lewis, State of Washington, have invented certain new and useful Improvements in Music-Leaf Turners; and I do hereby declare the following to be a full, clear, and exact description of the invention, such as will enable others skilled in the art to which it appertains to make and use the same.

This invention relates to new and useful improvements in music leaf turners.

One object of the present invention is to provide a device of this character which is simple in construction and durable and effective in operation.

Another object is to provide a device of this character wherein the player need not use his hands or feet to turn the music leaves, thus relieving him of removing his hands from the keys of the piano or organ, and his feet from the pedals.

Another object is to provide a novel and effective means for turning the music leaves first in one direction and then in the other.

Other objects and advantages will be apparent from the following description when taken in connection with the accompanying drawing.

In the drawing:

Figure 1 is a front elevation of my improved music leaf turner shown in connection with the music rest and front board of a piano.

Fig. 2 is a top plan view of the same.

Fig. 3 is a side elevation of the same.

Fig. 4 is a vertical sectional view taken on the line 4—4 of Fig. 1.

Fig. 5 is a horizontal sectional view taken on the line 5—5 of Fig. 1.

Fig. 6 is a horizontal sectional view taken on the line 6—6 of Fig. 1.

Fig. 7 is an enlarged vertical sectional view taken on the line 7—7 of Fig. 1.

Fig. 8 is a perspective view of one of the knee levers.

Fig. 9 is an enlarged vertical sectional view taken on the line 9—9 of Fig. 1.

Referring particularly to the accompanying drawing 10 represents the front board

of the piano, 11 the movable music board, and 12 the music ledge carried by the piano below and in front of the board 10.

Disposed against the music board 10 is a base board 13 of the leaf turning device. Through the board, adjacent each of the four corners, there is formed an opening 14, and through this opening is disposed the stem 15 of a clamp member. This clamp member includes the block 16 and the stem 15, before-mentioned, said stem being externally threaded and receiving thereon the clamping nut 10' for holding the block on the board, and the slideable hook rod 17 adjustable through the block by means of the set screw 18. The upper hooks engage over the upper edge of the front board of the piano, or the upper edge of the music board 11, while the lower hook members engage under the lower edge thereof. These hook members are provided with felt linings 19 for the purpose of protecting the polished surface of the piano. By reason of the adjustable features of the clamps it is readily seen that the base board of the device is capable of attachment to pianos of different designs and sizes.

Carried by the lower central portion of the outer face of the base board is a bracket 20, and carried by the central portion of the upper end of the board is a bracket 21. The upper bracket extends upwardly above the board, and thence outwardly, as clearly shown, while the lower bracket extends outwardly from the face of the board. Disposed vertically through these brackets, and in front of the board, is a shaft 22, the upper end of which is bent laterally to the right beyond the board, as at 23, while the lower end is bent laterally to the right and beyond the board, as at 24. Each of these portions 23 and 24 is provided with the leaf engaging clips 25, which grip the top and bottom edges of the leaf to be turned.

Loosely rotatable on the upper and lower portions of the shaft 22 are the tubular shafts 26 and 27, each having on one end a pinion 28, that on the former being on the lower end while that on the latter is on the upper end. Adjustable on the shaft 22 are the stop collars 29 which serve to hold the

tubular shafts in proper position on the shaft 22. The upper end of the shaft 26 is provided with a laterally and upwardly turned arm 30 which normally extends toward the left, while the lower end of the shaft 27 is formed with an arm which extends laterally toward the right and thence downwardly, as shown at 31. The upwardly extending portion of the arm 30 is arranged 10 to engage and move the upper leaf arm 23 while the lower arm 31 is arranged to engage and move the lower arm 24. In the first instance the leaf arms are turned to the right, while in the other instance the arms 15 are turned to the left.

Extending through the base board 10 adjacent the pinion of the upper shaft 26 is a shaft 32 on the outer end of which there is mounted a segmental gear 33 engaging with 20 the pinion of the shaft. On the lower portion of the board, adjacent the pinion of the shaft 27 is a similar shaft 34 having a segmental pinion 34' on its outer end engaging with the pinion of the shaft 27. The other 25 end of the shaft 32 is provided with an arm 35 to the outer end of which is connected one end of a cord or wire 36, while a cord or wire 37 is connected to one end of a similar arm 38 on the shaft 34. These wires extend upwardly and over grooved wheels or pulleys 39 mounted on the inner face of the upper 30 end of the music board of the piano. Mounted within the piano, inwardly of the front board thereof, and in line with the bottom face of the lower board of the key rest of the piano, are pulleys 40 around which the wires pass. The wires pass through the front of the piano where they are connected to the laterally extending arms 41 of the 40 knee engaging members 42. These members 42 are pivotally mounted in brackets 43 carried by the bottom board of the key rest, and have the outwardly extending blades 44 which are arranged to be pushed sidewise 45 by the knees of the player to draw the wires and cause the rocking of the segmental pinions. The movement of either of these pinions turns the engaged pinion of the tubular shaft and by reason of the engagement 50 of the arm on said shaft the leaf arm will be swung to one side and the leaf be turned. Connected to each of the segmental pinions is one end of a coil spring 45, said spring 55 normally holding the pinion, resiliently, in position for actuation, and returning the same to its normal or initial position.

It will be noted that the upper pinion 33 is arranged to turn the shaft 26 toward the right, while the pinion 34' is arranged to turn the shaft 27 toward the left. Thus when the player desires to turn the leaf toward the left he simply presses the right blade with his right knee which results in the wire connected thereto pulling the pinion

34' and rotating the shaft 27, with the result 65 that the arm of said shaft will engage with the lower leaf arm and swing the same, together with the leaf, toward the left. When pressure is released from the blade 44 the spring of the pinion 34' returns the pinion 70 to normal position, and rotates the shaft 27 so that the arm at the lower end thereof will be restored to its initial position at the right hand side of the board. When the leaf is to be turned back to its original position, that 75 is at the right hand side of the board, the left knee of the player is pressed against the other blade 44, with the result that the upper tubular shaft will be turned by the upper pinion 33, and the arm at the upper end of 80 the shaft 26 moved to engage and swing the upper arm of the leaf holding member. Thus the leaf is restored to position to be again turned when desired by the player.

What is claimed is:

1. A music leaf turner including a base member, a vertical shaft mounted on the base member, leaf turning arms on the ends of the shaft extending in a common direction and movable with the shaft, members rotatable on the end portions of the shaft, an arm on one of the rotatable members extending in one direction for engagement with one of the leaf turning arms to turn the shaft in one direction, an arm on the other rotatable member extending in the opposite direction for engagement with the other leaf turning arm to turn the shaft in the opposite direction, rocking elements on the base member and engaging with the rotatable members, and means operable by the knees of the player for independently actuating the rocking elements.

2. A music leaf turner including a base member, a rock shaft mounted vertically on the base member and having leaf engaging arms on the upper and lower ends thereof extending in a common direction, tubular shafts rotatable on the upper and lower portions of the shaft, an angular arm on one end of each of the tubular shafts for engagement with one of the leaf engaging arms, said angular arms normally extending in opposite directions, segmental pinion members mounted on the base member, pinions on the tubular shaft meshing with the segmental pinions, and means actuated by the knees of the player for moving the segmental pinions.

3. A music leaf turning device including a base member, a vertical shaft mounted for rocking movement on the base and having a pair of leaf turning arms on the ends thereof and extending in a common direction, a sleeve rotatable on one end of the shaft inwardly of the adjacent arm, a sleeve rotatable on the other end of the shaft inwardly of the adjacent arm, pinion members carried by the sleeves, segmental pinions

mounted on the base and engaging with the pinion members of the sleeves, resilient means for holding the segmental pinions in normal position, an arm on one of the sleeves 5 extending in one direction for engagement with one of the leaf turning arms to turn the shaft in one direction, an arm carried by the other sleeve for engagement with the other leaf turning arm to turn the shaft in

the opposite direction, and means for separately rocking the segmental pinion members.

In testimony whereof, I affix my signature in the presence of two witnesses.

CLAUDE HURN.
